UNITED STATES PATENT OFFICE.

GEORGE A. HULL, OF CHICAGO, ILLINOIS, ASSIGNOR TO EQUIPMENT SPECIALTIES CO.,
OF CHICAGO, ILLINOIS, A CORPORATION OF ILLINOIS.

FASTENER FOR THE FLOOR RACKS OF RAILROAD CARS.

Application filed December 11, 1924. Serial No. 755,201.

To all whom it may concern:

Be it known that I, GEORGE A. HULL, a citizen of the United States, and resident of Chicago, in the county of Cook and State of Illinois, have invented certain new and useful Improvements in Fasteners for the Floor Racks of Railroad Cars, of which the following is a full, clear, concise, and exact description, reference being had to the accompanying drawings, forming a part of this specification.

The present invention relates to fasteners for the floor racks of railroad cars.

In the construction of refrigerator cars it is the general practice to provide floor racks upon which the crates of fruit or other perishable produce are packed, to support the produce above the floor and provide a lower zone through which cold air can be circulated from the end ice compartments up through the perishable produce. These floor racks are generally hinged along their outer side edges, and when the car is to be cleaned, or is to be used for other purposes where the racks would be unnecessary or a hindrance, they are swung up to lie substantially parallel with the side walls of the car. Various forms of fastening devices have heretofore been employed for holding these floor racks in their upright positions, one typical form comprising a fastening member which is secured to the side wall and which supports a link adapted to be dropped over a strut on the rack. Fastening devices of this type are all subject to the objection that the fastening element on the side wall of the car forms a projecting obstruction which damages fruit crates and other commodities in the car. When the car suddenly stops and starts, or is suddenly jerked in the coupling of cars, the load has a tendency to shift in the car, with the result that the projecting fastener element often rips open the sides of the fruit crates and otherwise injures that portion of the load sliding past it.

The primary object of the present invention is to avoid this source of loss by providing a fastening which leaves no portion projecting in position where it can do any chafing, marring or tearing of the cargo while in transit.

A further object is to provide a fastening means of flexible nature for permitting en-

gine shocks to be absorbed by the floor rack 55 swinging against the car wall.

And a further object is to provide such a fastening means which will be cheap to manufacture and easy to apply.

Referring to the accompanying drawings 60 wherein I have illustrated a preferred embodiment of my invention:

Figure 1 is a fragmentary transverse sectional view of one side of a refrigerator car 65 showing one of the floor racks;

Figure 2 is a detail sectional view showing the manner of attachment between the link member and the recessed socket member;

Figure 3 is a front elevational view of the recessed socket member, taken on the plane 70 of the line 3-3 of Figure 2;

Figure 4 is a view similar to Figure 1 illustrating a modified form of fastening means;

Figure 5 is a front elevational view of the 75 socket member employed in this embodiment illustrating in dotted lines the floor rack in its upper position, and

Figure 6 is a detail sectional view illustrating a modified attachment between the 80 fastener link and the floor rack.

Referring to Figure 1, the floor of a refrigerator car is indicated at 8 and one side wall at 9. This side wall 9 is generally built up of outer sheathing 11, a layer of hair felt 12, post 13, other layers of hair felt 14, and an inner wall facing 15. The inner wall facing 15 is spaced from the innermost layer of hair felt 15 for providing 85 an intervening air space 16.

The floor rack 18 is constructed of longitudinal stringers 19 which normally rest on the floor 8, and across the upper edges of which are fastened cross members 21. These floor racks usually extend from the bulkhead 95 defining the end ice compartment to the central portion of the car, and there are generally two of these floor racks transversely of the car, one for each side thereof.

In providing pivotal or hinged connections for the outer edges of these floor racks, a stringer 23 is nailed to the floor against the side wall 9. Extending upwardly from this fixed stringer 23 at spaced intervals 105 are stationary eye-bolts 24, the nuts 25 of which engage in counterbores 26 in the under side of the stringer. Projecting laterally from the adjacent stringer 19 of the

floor racks are cooperating eye-bolts 27 held in the stringer by nuts 28. Pivot pins 31 pass through the aligned eyes of these cooperating pairs of eye-bolts.

5 When the floor rack is swung up along side of the side wall 9, it occupies substantially the position indicated in dotted lines. The floor rack is held in its upper position by a link member carried by the floor rack 10 engaging with a socket member recessed in the side wall 9. This link member comprises an eye-bolt 33 extending upwardly through the outer stringer 19 and receiving a nut 34 at its lower end engaging in a 15 counterbore 35. A pair of chain links 36-36' have linked connection with the eye in this latter eye-bolt. The bolt is extended through the stringer to dispose the eye 37 intermediate adjacent cross members 21, 20 and when the rack is in its lower position, the two links 36-36' can be dropped down between these cross members where they will not interfere with the sliding of crates on the floor rack.

25 The cooperating socket member 38 is in the form of a cup-shaped shell which is recessed in an opening in the siding 15. This cup-shaped shell is preferably extended back through the air space 16 to obtain the desired depth of socket, in the arrangement shown the rear face of this socket abutting the adjacent layer of hair felt 14. A marginal flange 39 on this socket is adapted to lie in a countersink in the face of the siding, the hole for the socket and the countersink for the flange 39 being capable of cutting at one operation.

The socket is provided with a locking shoulder adapted to be engaged by the fastening link carried by the floor rack 18. 40 This locking shoulder is in the form of a hook 41 formed integral with the shell 38 and projecting radially from the inner wall thereof. When the floor rack has been 45 swung to its upright position, the end fastening link 36 is merely inserted in the socket and slipped over the hook 41. The play afforded through the links 36-36' avoids any necessity of accurate alinement between 50 the fastening means and absorbs engine shocks by permitting the floor rack to swing inwardly toward the side wall. When the floor rack is lowered to its normal position on the floor 8, it will be noted that no part 55 of the fastening member carried by the side wall projects beyond the plane of the side wall.

The socket 38 may be secured in the side wall by wood screws 43 passing through 60 apertures in the flange 39 and screwing into the siding 15. Another manner of fastening this socket for interlocking the same to the siding 15 is to slot the upper part of the shell at 44 and pass an interlocking angle member 45 up through this slot for engage-

ment on the outer side of the siding 15. The lower end of this angle member 45 is apertured for the reception of a long wood screw 46 which passes through the intervening layers of hair felt 14 and screws into the post 13. When using the interlocking angle member 45, the outer wood screws 43 can be dispensed with if desired. Conversely, the screws 43 may be employed without the interlocking angle member 45. 75

In the embodiment illustrated in Figures 4, 5 and 6 the fastener link carried by the floor rack consists of a shank 48 having a ball 49 at one end and an eye-pivot 51 at the other. The eye 51 is looped through a 80 hole in the upper edge of a plate 52 which is secured to the outer side face of the stringer 19 by screws 53. When the floor rack reposes in its lower position on the car floor, the link can drop down between 85 adjacent cross members 21, whereby no portion of this fastening means will project above the top of the floor rack.

The socket member carried by the side wall in this embodiment consists of a rectangular plate 54 which is recessed in a countersink in the siding 15. The socket member is secured to this siding by screws 55. Formed in this socket plate 54 is a keyhole slot consisting of a relatively large 95 opening 56 and a narrow slot 57 extending downwardly therefrom. The portion of siding immediately behind this keyhole slot is cut away to form a recessed area. 90

When the rack has been swung to its upright position, the ball end 49 of the fastening means on the rack 18 is inserted through the upper end 56 of the keyhole slit and is then dropped down behind the narrow portion 57 thereof. The lateral 105 edges of the narrow portion 57 form locking shoulders for cooperating with the fastener link 48. As described in the previous embodiment, the play incident between the link 48 and the rack avoids any necessity 110 of accurate alinement between the two fastening devices and permits of a limited swinging movement of the rack for absorbing engine shocks. 100

In the modification illustrated in Figure 6, the fastener link 48 has connection through one or more chain links 49 with the eye 51 of an eye-bolt 52 extending through the stringer 19. This affords a still 115 greater freedom of the link 48. 120

I do not intend to be limited to the particular details herein shown and described.

What I claim is:

1. In a railroad car, the combination of a side wall, a floor rack adapted for swinging up into proximity to said side wall, a fastening member hingedly connected to said floor rack, and a socket member comprising an annular metal wall set into a recess in said side wall of the car and closing the sides 125

of said recess, said socket member having a locking shoulder therein with which said pivoted fastening member is adapted to have locking co-operation.

5 2. In a railroad car, the combination of a side wall, a floor rack adapted for swinging up into position alongside said side wall, a fastening member carried by said floor rack, and a socket member comprising an 10 annular metal wall set into a recess in said side wall, said socket member having a locking shoulder therein with which said fastening member is adapted to have locking co-operation.

15 3. In a railroad car, the combination of a side wall, a floor rack adapted for swinging up into proximity to said side wall, a fastening member pivotally connected to said floor rack, and a socket member set into a recess 20 in said side wall, said socket member comprising an outer flange engaging said side wall for receiving fastening screw means and having a locking shoulder with which said fastening member is adapted to have 25 locking co-operation.

4. In a railroad car, the combination of a side wall, a floor rack adapted for swinging up into position alongside said side wall, a link member pivotally connected to said 30 floor rack, and a socket member set into a recess in said wall and having a locking shoulder for receiving said link, said socket member comprising an outer flange apertured to receive screws for fastening the same to 35 said side wall.

5. In a railroad car, the combination of a side wall, a floor rack adapted for swinging up into proximity to said side wall, a fastening link hingedly connected to said floor 40 rack, and a socket member comprising a flanged portion set into a recess in said side wall and comprising a locking shoulder with which said fastening link is adapted to have locking co-operation.

45 6. The combination with a railroad car having a side wall and a floor rack adapted for swinging up into position alongside said side wall, of fastening means for said floor rack comprising a fastening member carried 50 by said floor rack and a cup shaped metallic socket set into a recess in the side wall and having a locking shoulder for co-operation with said fastening member.

55 7. In a railroad car, the combination of a side wall and a hinged floor rack, a cup-shaped socket member recessed in said side wall, said socket member having a locking shoulder therein, and a link carried by said rack adapted for engagement with said locking shoulder.

8. In a railroad car, the combination of a side wall and a hinged floor rack, a cup-shaped socket member having a hook therein, said socket member being recessed in 60 said side wall, and a link carried by said

rack having a looped end adapted for engaging over said hook.

9. In a railroad car, the combination of a side wall and a floor rack adapted to be swung up into position alongside said side 70 wall, fastener means for securing said rack to said side wall comprising a socket member recessed in said side wall, and a member projecting from said socket member and engaging on the rear side of a portion of said side 75 wall.

10. In a railroad car, the combination of a side wall and a floor rack adapted to be swung into position adjacent said side wall, fastener means for connecting said rack to 80 said side wall comprising a socket member recessed in said side wall, and a link member carried by said floor rack and an interlocking shoulder projecting from said socket member and engaging on the rear side of the 85 panelling of said side wall.

11. In a railroad car, the combination of a side wall, a floor rack adapted to be swung up into position alongside said wall, fastener means for attaching said floor rack to said 90 side wall comprising a cup-shaped socket member recessed in said side wall, and a link pivotally connected to said floor rack and adapted for engagement in said socket member, one wall of said socket member having 95 a slot therein, an interlocking member adapted to be inserted out through said slot after mounting on said socket member in said side wall, said interlocking member being adapted to be engaged behind a portion of said side wall. 100

12. In a railroad car, the combination of a side wall, a floor rack adapted to be swung up into position alongside said side wall, a socket member secured to said side wall having a slot therein, and means carried by 105 said rack adapted for engagement in said slot.

13. In a railroad car, the combination of a side wall, a floor rack adapted to be swung up into position alongside said side wall, a socket member secured to said side wall having a slot therein, and a link pivotally connected to said rack for engagement in said slot. 110

14. In a railroad car, the combination of a side wall, a floor rack adapted to be swung up into position alongside said side wall, a socket member secured to said side wall having a keyhole slot therein, and a link member connected to said rack and having a laterally projecting surface adjacent the end thereof for engagement in said keyhole slot. 120

15. In a railroad car, the combination of a side wall, a floor rack adapted to be swung up into position alongside said side wall, a socket member secured to said side wall having a keyhole slot therein, and a link pivotally connected to said rack and having 125 130

- a ball end adapted for dropping into said keyhole slot.
16. In a railroad car, the combination of a side wall, a floor rack adapted to be swung up into position alongside said side wall, a socket member secured to said side wall having a keyhole slot therein, a link having a spherical end adapted for insertion in the large part of said keyhole slot and 10 for dropping behind the locking shoulders of the narrow portions of said slot, and a second link loosely connecting said locking link with said floor rack.

17. In a railroad car, the combination of a side wall, a floor rack adapted to be swung 15 up into position alongside said side wall, an eye-bolt secured to said floor rack, a fastener link carried by said eye-bolt, and a cooperating fastener member carried by said side wall for engagement with said 20 fastener link.

In witness whereof, I hereunto subscribe my name this 9th day of December, 1924.

GEORGE A. HULL.

Witness:

CAMERON A. WHITSETT.
